UNITED STATES PATENT OFFICE.

DAVID J. MCKENNA, OF ENGLEWOOD, NEW JERSEY.

FLOUNCE FOR PETTICOATS.

948,821.

Specification of Letters Patent. Patented Feb. 8, 1910.

Application filed November 16, 1909. Serial No. 528,351.

To all whom it may concern:

Be it known that I, DAVID J. MCKENNA, a citizen of the United States, residing at Englewood, in the county of Bergen and State 5 of New Jersey, have invented certain new and useful Improvements in Flounces for Petticoats; and I do hereby declare the following to be a full, clear, and exact description of the invention, such as will enable 10 others skilled in the art to which it appertains to make and use the same.

This invention relates to improvements in wearing apparel and more particularly to flounces for petticoats.

15 The object in view is the provision in a petticoat of a body portion the full length of a skirt and a flounce made independent thereof but stitched thereto.

Another object of the invention is the arrangement in a petticoat of a body portion 20 and an independent flounce secured to the body portion by a line of stitching, the flounce being formed with a draw string arrangement for adjusting the size of the 25 flounce to the body portion.

A still further object of the invention is the provision of a flounce so formed as to be readily securable to any skirt or petticoat.

With these and other objects in view the 30 invention comprises certain other novel constructions, combinations and arrangement of parts as will be hereinafter more fully described and claimed.

In the accompanying drawing:—Figure 1 35 is a view of a petticoat including a flounce embodying the invention. Fig. 2 is a perspective view of the flounce removed. Fig. 3 is a large detailed fragmentary sectional view of Fig. 1 approximately at line 3—3 40 thereof.

In forming a petticoat embodying the invention a body portion is constructed in any desired manner for giving the proper set thereof which may receive an independent 45 flounce which is secured thereto by one or more lines of stitching. The body portion is made preferably plain while the flounce is made of either the same grade of material as the body portion or of better material 50 and is also preferably made more or less fanciful in appearance. The upper edge of

the flounce is turned over and secured by a line of stitching for accommodating a draw string whereby the flounce may be gathered more or less at the upper edge as desired for 55 fitting the body portion or for improving the appearance of the flounce.

The principal idea in forming the flounce as set forth is that the same may be secured to the body portion of any petticoat either 60 one specially made therefor or to a skirt which has had a flounce removed therefrom. This is of great advantage in that one can make a body portion and then simply buy a flounce and secure the same thereto by a line 65 of stitching so that the completed skirt will have a finished appearance and yet will have a proper fit or set that the person desires.

In order that the invention may be more 70 clearly understood, an embodiment of the same is shown in the accompanying drawing in which 1 indicates a body portion and 2 the flounce as a whole. The flounce 2 may be formed of any kind of fancy work at the 75 lower edge 3 and over the surface thereof as desired. At the upper edge the flounce is turned over forming an inner flap 4 which extends entirely around the flounce and is held in place by a line of stitching 5 which is 80 interrupted at the point 6 for permitting a draw string 7 to be operated in the space provided therefor by the turning over of the upper edge of the flounce. The draw string 7 is pulled or drawn and the flounce 85 properly adjusted thereon until the upper edge thereof is of proper size to secure to the lower edge of the body portion 1. The draw string is then tied or left untied as preferable. After the flounce has been 90 adjusted to the body portion 1, the same is secured in position preferably by one or more lines of stitching 8. By thus arranging the body portion of the petticoat independent of the flounce, any desired flounce 95 may be fitted to any body portion. Also if desired, the flounce can be ripped off the body portion and a new flounce secured thereto. It will be noted in addition that a flounce may be made of more or less expensive material and the body portion of 100 cheaper material and yet a substantially

integral and continuous petticoat is provided.

What I claim is:—

In a petticoat, a body portion, a flounce therefor formed with a turned over flap, a line of stitching for holding said flap in position, a draw string inclosed by said flap arranged to adjust the size of the flounce and

a line of stitching for securing the flounce to the body portion.

In testimony whereof I affix my signature in presence of two witnesses.

DAVID J. MCKENNA.
